UNITED STATES PATENT OFFICE.

HORACE JOHN LEACH, OF MOUNT CARMEL, ILLINOIS.

SEWING-CABINET.

1,277,956.

Specification of Letters Patent.

Patented Sept. 3, 1918.

Application filed December 31, 1917. Serial No. 209,732.

To all whom it may concern:

Be it known that I, HORACE J. LEACH, a citizen of the United States, and a resident of Mount Carmel, in the county of Wabash and State of Illinois, have invented a new and Improved Sewing-Cabinet, of which the following is a full, clear, and exact description.

This invention relates to cabinets designed for use especially by seamstresses and has particular reference to a simple and compact article adapted for holding various articles such as tools or supplies in a readily accessible and secure manner so that any householder can always know where to find anything she desires to use, for mending, repairing, etc.

Among the objects of the invention, therefore, is to provide a cabinet adapted to be supported against a wall or upon a suitable base and including in its assemblage compartments for needles, pins, thimbles, scissors, yarn, cotton or thread of different characters, buttons, hooks and eyes, etc.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation, parts being in section and other parts being drawn out to better disclose the novel features.

Fig. 2 is a vertical transverse section on the line 2—2 of Fig. 1; and

Figs. 3 and 4 are plan and side views of one of the supporting feet for the device when it is to be supported upon a table or the like.

Referring now more particularly to the drawings I show a device adapted preferably to be made of sheet metal which may be suitably ornamented or decorated to present an attractive appearance as well as possessing strong features of utility.

In the form of the invention illustrated I provide three horizontal and therefore parallel tubular containers 10, 11 and 12, supported by vertical end pieces 13 and 14 whereby the three containers are held in rigid relation to one another. The contain-

ers 10 and 12 could be described as segments of hollow cylinders or as of cylindrical form with a probable small segment or slice removed from the top of each. These containers are closed except for one open end into or through which a drawer 15 or 16 is projected. The outer end of each drawer has a cap 17 and finger piece 18 for manipulation of the drawer. The cap constitutes a closure for the container when the drawer is closed. Each of these drawers may be partitioned off as indicated at 19 to provide any suitable number of smaller compartments for holding various sizes or types of buttons, snap fasteners, hooks and eyes, or other needful small articles. The cross sectional form of these drawers affords two important results or conditions as follows: From the nature of the articles designed to be held in the several compartments the rounded bottom makes it exceedingly easy for the small articles to be removed with one's fingers, a result which could not so easily or readily be accomplished if the drawers were formed with angles at the bottom. Secondly, the segmental form of the top insures against the rotation of the drawers and the spilling of the contents.

The container 11 is designed to accommodate a considerable number of spools of silk or sewing thread, as indicated at 20, the several spools shown as slipped upon a spindle 21 fixed to the closed end of the container, while the other end of the spindle is unsupported. A closure cap 22 is adapted to close the container 11 and so prevent the spools from slipping off of the spindle. At either the front or rear of the container 11 is hinged a lid or flap 23 which extends from the top well down over the side of the container and which upon being lifted will give relatively free access for the inspection of the condition of the thread on the several spools or for grasping the loose ends of the thread. The loose ends, however, ordinarily hang free below the flaps 23 so that when a piece of thread is desired the seamstress merely grasps the free end thereof and draws out as much as desired, when it may be severed from the spool by use of a thread cutter of any desired nature such for example as the sharpening of one of the free edges of one end piece as at 24. With a thread cutter so arranged outside of the container 11 the end of the thread will dangle somewhat below the opening so as to be

in position to be grasped on the next occasion. The thread on the spools will thus be kept not only in a known position but in a condition most favorable for the thread.

5 When a spool is empty it may be removed from the free end of the spindle and another spool put in its place, the end of the thread first being loosened so as to be projected through one of the openings beneath the

10 flap 23. The cap 22 will then be replaced.

Above the central portion of the container 10 is arranged a sort of open arch structure 25 serving a number of different functions as follows: The top thereof supports 15 a pin and needle cushion 26, beneath which is fixed a hook 27 for a button hook or other device. The sides of the arch 25 on opposite sides of the cushion 26 are provided with a plurality of holes 28 for supporting 20 thimbles or the like. Beneath the arch is arranged a tray 29 which may contain an oil can or implements commonly used around a sewing machine, such as a screw driver, wrench or the like. The needle cushion includes 25 inner and outer collars 30 and 31, the inner collar being fixed to the top portion of the arch and is thus adapted to permanently hold a supply of saw dust, ground cork or the like, indicated at 32 over which one or more plies of fabric 33 are adapted 30 to be stretched and removably clamped in place by means of the outer removable collar 31 so that if the fabric becomes faded, soiled, or worn, it may be easily replaced 35 by another without disturbing the filler 32 of the cushion.

In connection with the arch structure I call attention at this time to the rear bracket 34, the upper end of which is fixed to the 40 top of the arch while the lower end of the bracket is fixed at 35 to the lowermost container 12. This bracket is slotted from the bottom up to a point adjacent to the top for coöperation with a plurality of fixed 45 fasteners such as screws 36 whereby the cabinet may be secured in reliable position against a wall and so will occupy a relatively small amount of space and in a position not likely to be disturbed, although it 50 may be easily removed from its supporting screws by simply lifting it therefrom when desired.

As an alternative means for supporting the cabinet I may employ a pair of feet such 55 as indicated in Figs. 3 and 4, each comprising a vertical web 37 having a central keeper

38 into which the lower end 39 of each end piece 13 or 14 may be slipped, and each having its ends turned over at 40 in order to make a more stable support for the cabinet 60 and reduce the likelihood of scratching or marring the table. The action of these alternative supporting means is indicated in dotted lines in Figs. 1 and 2.

At the top of the cabinet and on each side 65 of the arch 25 are arranged other containers 41 and 42 each having a lid 43. These containers may be employed for holding such commodities as crochet thread and darning cotton.

In front of the containers 41 and 42 are secured a pair of scissors holders 44, shown as two in number each in the nature of a slender funnel and arranged in an inclined position so that the scissors will not be likely 75 to drop therefrom.

I claim:

1. The herein described sewing cabinet comprising a plurality of horizontal parallel tubular containers, vertical end pieces supporting the containers, at least one of the containers having a slideable drawer for containing small articles in dust-proof condition, said drawer having a rounded bottom and so shaped as to be held from rotation, 80 and another of the containers being adapted to contain a series of spools of thread, and means to support the device in erect position.

2. The herein described sewing cabinet comprising a plurality of horizontal parallel 90 containers, vertical end pieces connected to and supporting the containers, one of said containers having a longitudinal central spindle fixed at one end and free at the other for slidably supporting a series of 95 spools, a closure for the end of the container adjacent to the free end of the spindle, and an opening through at least one side of the container through which the thread may be inspected and manipulated.

3. The herein described sewing cabinet comprising a plurality of parallel horizontal tubular containers each having an end closure, other containers above the first mentioned containers and adapted to contain 105 darning cotton, crochet thread or the like, and a plurality of scissors holders in the nature of slender funnels secured in inclined position in front of the last mentioned containers, substantially as set forth.

HORACE JOHN LEACH.
